(57) **CLAIM**

The ornamental design for a display screen for operator for medical X-ray imaging equipment with graphical user interface as shown and described.

DESCRIPTION

FIG. 1 is a perspective view of a display screen for operator for medical X-ray imaging equipment with graphical user interface showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is bottom view a thereof.

The broken lines in the drawings represent portions of the display screen for operator for medical X-ray imaging equipment with graphical user interface that form no part of the claimed design.

1 Claim, 7 Drawing Sheets
